MAKING LASTS

Clifford K. MacDonald, Brockton, Mass., assignor
to United Shoe Machinery Corporation, Paterson, N. J., a corporation of New Jersey

Application August 8, 1932, Serial No. 627,870

37 Claims. (Cl. 12—142)

This invention relates to lasts and methods of making lasts and is illustrated herein with reference particularly to the manufacture of lasts and last models, adapted for use in the manufacture of both ordinary shoes and orthopedic shoes of the character disclosed in United States Letters Patent No. 1,039,396, granted September 24, 1912, upon an application of Mathew Hilgert. It should be understood, however, that in various of

10 its aspects the invention is adapted to use in the manufacture of shoes of other types.

It is well known by foot specialists and doctors generally that feet of different individuals differ widely in shapes and proportions as well as in sizes and that even the two feet of a given individual will often exhibit such differences. The diversity in outline of the feet of different persons is partly congenital and is partly caused by different foot postures and by the characteristic 20 gaits and different foot activities of different individuals. One example of the diversity in the shape of feet may be found from a comparison of the upper surfaces of various feet. This upper surface or dorsum curves in two directions, one 25 curve starting at the heads of the metatarsal bones and extending backwardly, and the other curve starting at the inner side of the foot and extending outwardly around the foot. This curvature is commonly referred to as the instep and its shape is governed largely by the height 30 of the longitudinal arch. The curvature of the instep not only varies markedly in the feet of different individuals but usually differs more or less in the feet of the same individual. A number of other variations in physical structure cause 35 the feet of one person to differ in shape from those of another, for example, feet having high arches will differ from those having low arches, and narrow feet will differ from broad feet, or 40 from fat, muscular or flabby feet. Any of these variations may exist in a normal foot since a foot is considered normal to an individual if it is capable of effectively performing its work, that is, if it is capable of supporting the weight of the 45 body, taking part in normal locomotion, and exhibiting the range of foot movements natural to a normal foot.

At the present time most of the shoes manufactured in this country are made on commercial wood lasts which are produced on last-making machinery constructed and arranged to turn wood lasts from selected last models. The various models utilized in making these wood lasts have certain standard measurements, such, for example, as the girths at the ball, waist and instep,

though differing considerably in shape and style in other respects. The lasts are graded from sizes appropriate for the largest feet to sizes appropriate for the smallest feet for which shoes are made commercially, the grading scheme being 5 irrespective of the styles of the lasts. It follows that the measurements of commercial lasts are substantially the same for all styles of shoes, that is to say, all lasts of a given length and width will have substantially the same basic measurements at the ball, waist and instep, since these measurements, having been found suitable for most feet, have been standardized. This does not mean that commercial lasts do not vary somewhat in shape at other portions thereof, for example, at the toe portions which may be a number of different shapes depending on the particular style of shoe desired, but it simply means that the portion of a last which determines its size with respect to the foot and which, therefore, 10 determines the fit of the shoe, namely, that portion extending between the ball line and the heel end of the last, has substantially the same basic 15 measurements in all commercial lasts of the same length and width regardless of their styles. 20

From the above it will be seen that, although commercial lasts reproduced from models on the usual last-making machinery may be properly suited to feet which are perfectly regular in shape, yet the present system of last-making 30 does not provide lasts upon which to make shoes suitable for feet which, although normal in so far as their capacity to support the weight of the body and to effect locomotion is concerned, are nevertheless different in shape from the general- 35 ity of feet which agree with the standard last measurements at the ball, waist and instep portions of the feet. Moreover, this system can not, of course, produce lasts suitable for feet which are completely broken down at the main arches 40 or which are afflicted with malady of the muscles, ligaments, or bones that make up and support these arches. Consequently, many cases exist where an individual is compelled to wear shoes which, although having the standard measure- 45 ments referred to, are nevertheless the wrong kind of shoes for him to wear because they do not conform properly to the shapes of all portions of his feet. Such shoes will not only be uncomfortable and irritating to his feet but may eventually bring on serious foot ailments. Many times foot ailments of a minor character have become chronic or even permanent because the persons afflicted could not get shoes which fitted their 50 feet properly in all respects. 55

It is an object of the present invention, therefore, to provide an improved process by which lasts may be made for use in the manufacture of both ordinary shoes and orthopedic shoes, as well as for use as models from which to make wood lasts for use in the manufacture of such shoes, the lasts being shaped to conform to the peculiar characteristics of the particular feet for which they are made, and, in the manufacture of orthopedic shoes, being adapted, if desired, to provide a definite amount of extra space for the insertion of a special filler piece between the foot of the wearer and the inside tread surface of the sole of the shoe.

15 In the practice of the present invention a novel method is employed for obtaining a last which is appropriate to the foot of a particular individual, this method consisting in making a cast of a foot, shaping the cast to the form of a last and utilizing the cast as a last or as a model to produce a wood last with the aid of the usual last-making machinery. The lasts produced in accordance with this method are adapted for use in the manufacture of ordinary shoes and orthopedic shoes.

20 25 In one aspect the invention contemplates reinforcing the surface of a cast appropriate in shape to the foot of the individual for whom the shoe is to be made, to produce a last the surface of which will be hard and smooth, and of a consistency that will enable the last to withstand the pressure and strain to which it will be subjected during the manufacture of a shoe, or while it is being utilized as a model for turning a wood last, without becoming broken, cracked, or otherwise mutilated during the operations involved in such processes.

30 35 In another aspect the invention contemplates producing an improved last which will be especially useful in the manufacture of orthopedic shoes in which the foot is supported by means of a filler piece inserted between the foot of the wearer and the inside tread surface of the shoe, the last being also adapted for use as a model from which to turn a wood last suitable for making orthopedic shoes. Preferably, and as illustrated, a cast of a foot is supported in a predetermined position above a last bed comprising a rectangular plate of wood or plastic material, the plate being considerably larger in dimensions than the bottom surface of the cast and having an upper surface shaped to conform to the bottom surface of a regular last which has a toe spring and heel height corresponding to the toe spring and heel height of the cast being used.

40 45 50 55 60 65 Plastic material is then added to the bottom surface of the cast to produce a form which will provide extra space in the finished shoe for the insertion of a special filler-piece adapted to support the foot in a properly balanced position in the shoe, the contour of the form being trimmed to the shape of a regular last after the plastic material has set.

A convenient way of carrying out this improved process will now be described, reference being made to the accompanying drawings, in which

70 Fig. 1 illustrates, in side elevation, a plastic cast of a foot properly positioned on the upper surface of a last bed which has a clay fence formed thereon around the lower portion of the cast;

75 Fig. 2 is an end elevation of the cast, last bed and fence shown in Fig. 1;

Fig. 3 shows the cast after plastic material has been added to its lower portion to provide sufficient material for shaping the cast to the form of a last;

Fig. 4 is a side elevation of the enlarged cast shown in Fig. 3 after the cast has been shaped to the form of a last;

Fig. 5 is a bottom plan view of the cast shown in Fig. 4;

Fig. 6 is a side elevation of the reinforced cast with a part broken away at the heel portion to show the successive coatings of reinforcing materials;

Fig. 7 is a sectional view of a portion of the 10 cast on an enlarged scale to show more clearly the reinforcing materials on the surface of the cast;

Fig. 8 is a view similar to Fig. 1 showing a 15 cast of an unbalanced foot supported in predetermined position on pins above the upper surface of the last bed;

Fig. 9 is an end view similar to Fig. 2 showing the position of the heel end of the supported cast;

Fig. 10 is a view similar to Fig. 3 showing the 20 cast after the addition of plastic material to provide sufficient material for shaping the cast to the form of a last which has a form added to its bottom surface to provide a space in the shoe for the insertion of a filler piece;

Fig. 11 shows the cast of Fig. 10 after it has been shaped to the form of a last; and

Fig. 12 shows a completed cast for use in the manufacture of orthopedic shoes.

In practicing the method of the present invention casts of the feet of the individual for whom the shoes are to be made are obtained from foot molds formed by pouring plastic material around the feet of the individual while the feet are supported in a molding box of any usual type. In order that the casts will conform to the shapes of the feet when the feet are supporting the weight of the body and in the positions they are to assume in the finished shoes, the molds are made while the feet are held in normal 40 upright positions, that is, with the vertical center lines at the back of the heel ends at right angles to the tread surfaces of the feet. With the feet in this position, the individual stands so that his weight is supported evenly by both 45 feet, thereby causing the feet to expand slightly at their base portions and to assume shapes natural only when the feet are in weight bearing positions. The natural expansion of feet which are supporting the weight of the body is between 50 one-sixteenth and one-quarter inch.

Since the casts are to be detailed duplications of the feet of the individual when the feet are in the positions they assume in the finished shoes, it is necessary to consider the heights of the heels 55 which are to be attached to the shoes in order that the heel ends of the feet may be positioned properly before the molds are made. Accordingly, the shoes which he is wearing are examined to determine whether the heights of the heels 60 are appropriate to his particular type of foot. If the shoes are found to have heels suitable in height to his weight and stature, and not causing his weight to be supported unevenly at the different weight-bearing points of the bottoms of the 65 feet, the heel end of each foot is raised relatively to the toe portion an amount equal to the height of such heel, so that each foot will be held substantially in the same position when making the impression in the foot mold as it is to assume 70 in the finished shoe. If, however, the heels which the individual is wearing on his shoes are found to be improper for his weight and stature, the heel ends of his feet are raised only an amount 75 which is considered suitable for his particular

type of foot. Thus, the impressions obtained in the molds will be exact reproductions of the shapes of the feet of the individual when he is standing with his weight bearing evenly on both

5 feet and with the feet in the positions they will assume in shoes having heels suitable in height to his weight and build as well as to the general condition of his feet.

It should be pointed out that in referring to the foot as supporting the weight of the body, in the description and claims, it is not meant to imply that each foot is supporting the entire weight of the body at the time the impression of that foot is made, but that each foot is merely supporting its proportionate share of the weight of the body, that is, the weight which would naturally fall on that foot when the person is standing normally on both feet.

20 After the impressions are made the feet are carefully measured and the measurements are recorded on a chart which is used for reference during later steps of the method. Since the impression in each mold is an exact reproduction of the shape of the foot from which it was
25 made, the molds may be used for producing a pair of casts 10, one cast for each foot, which are exact duplications of such feet. The casts 10, one of which is shown in Fig. 1, are made in the usual manner by pouring a plastic material into the impressions in the foot molds and allowing the plastic material to set before removing the cast from the mold. They may be made from a plastic material such as plaster of Paris or any equivalent thereof that will harden sufficiently to
30 form a solid article. It has been found in practicing the method of the present invention, however, that a plastic composition known as "Hydrocal" and consisting of marble dust mixed with a binding agent such as plaster of Paris or gypsum
35 is preferable for this purpose because, while it is substantially as light as other plastic substances of this nature and will harden sufficiently to form a solid cast, it sets without undue brittleness. It is to be understood, however, that the
40 terms "plastic material" and "Hydrocal" used in the specification are merely descriptive and are intended to include plaster of Paris or any of its equivalents that can be used for making a cast of a foot. After the casts 10 have set a vertical
45 center line 13 is drawn on the back of the heel portion of each cast, as shown in Fig. 2.

55 Since the bottom surfaces of the casts are detail duplications of the features of the bottoms of the feet from which they were made, accurate measurements may now be obtained from each cast to determine the position of the transverse arch relatively to the heel end of the foot. By measuring across the forepart of each cast 58, with the cast inverted and positioned so that the vertical center line of the heel end is at right angles to the horizontal, the positions of the arches relatively to each other and to the heel end of the foot may be found. In this way, it 60 may be determined whether the foot of the individual is in a balanced or an unbalanced condition with respect to the main arches of the foot. If these measurements disclose a displacement of the arches of either foot, a filler-piece may be 65 inserted in the shoe to support the arches and to lift them into corrective positions relatively to each other. Shoes having a space provided for the insertion of a filler piece are disclosed in Letters Patent No. 1,039,396 previously mentioned. This lifting of the displaced arches tends 70 75

to relieve the strain on the muscles and ligaments of the arches and to restore the entire muscular organization of the foot to a normal balanced condition.

Two sole patterns 11 are now made by setting the casts upright on a piece of thin cardboard or paper and tracing a line on the paper around the bottom surface of each cast. The length of each pattern is determined by measuring the length of its corresponding cast with a standard last stick and adding three sizes to the measurement of the cast in order to obtain a length suitable for the sole pattern. This length is then marked off on the paper by measuring from the heel end of the tracing and the toe portion of the tracing is extended until it coincides with the mark on the paper. The toe portion of the sole pattern is gradually tapered until it is appropriate in shape for the foot from which the cast was made. The outline of the other portions of the pattern corresponds substantially to the measurements and contour of the bottom surface of the foot. The two patterns are then cut out on the lines thus drawn.

The next step in the method is to produce a pair of casts which will be appropriate in size and shape to the feet of the individual for whom the shoes are to be made. One of the sole patterns 11 is placed on the upper surface of a last bed 12 comprising a rectangular plate of wood or plastic material, the plate being considerably larger in dimensions than the bottom surface of the cast. The upper surface of the last bed or plate, as shown in Fig. 1, is shaped to conform to the bottom surface of a regular last having a toe spring appropriate for the shape of the cast being used. The portion of the last bed which supports the heel end of the cast is so formed as to correspond in thickness to the height of heel desired on the finished shoe so that the cast may be positioned longitudinally approximately at the same angle at which the foot is to be supported in the finished shoe.

If the measurements of the bottom surfaces of the casts indicate that no unbalanced conditions exist with respect either to the longitudinal or the transverse arches of the feet, each cast is positioned directly on the paper pattern. Since filler pieces will not be required in the finished shoes, certain intermediate steps of the process disclosed herein may be eliminated and the operations of adding plastic material to the cast, shaping the cast to the form of a last, and reinforcing the cast may be begun as soon as the cast has set sufficiently to permit such operations to be performed. 55

After the cast has been placed on the pattern 11, a clay fence 20 is built on the last bed 12 around the cast 18 to form an enclosure completely around the base of the cast, a modeling clay such as plasticine being used for this purpose. The fence should extend upwardly from the last bed a distance approximately equal to half the height of the cast and should correspond in outline to the contour of the paper pattern 11. Also, the fence should be built as close to the edge of the sole pattern as can be done without disturbing either the pattern or the cast. Fig. 1 shows the cast positioned on the last bed and having the fence built around the pattern to form an enclosure around the cast.

"Hydrocal" 22 is now poured into the enclosure thus formed to fill the spaces between the last bed 12 and the bottom surface of the cast 10. The toe and heel portions of the cast are also 75

covered with "Hydrocal" to fill in the depressions and irregularities formed by the toes at the fore-part of the cast, and the inwardly curved portions at the base of the back of the heel. The 5 foot being normal and the cast having been placed directly on the paper pattern, the only spaces that will exist between the cast and the upper surface of the last bed are under the arched portions of the bottom surface of the cast and 10 beneath the toes. After the "Hydrocal" has set, the cast is removed from the last bed together with the paper pattern, the latter now adhering to the bottom surface of the cast as shown in Fig. 3. The length of the cast will, of course, be 15 increased at its lower portion by an amount corresponding to the length of the enclosure or fence built around the paper pattern.

The next step in the method of making lasts disclosed herein consists in shaping the bottom 20 of the "Hydrocal" cast 10 to the contour of the sole pattern 11 which has adhered to the bottom surface of the cast, and in rounding and shaping the toe and heel portions of the cast to the form of a regular last in accordance with 25 standard last measurements computed from the measurements of the foot which were taken from the original cast. This step is performed by means of scrapers or hand tools suitable for the purpose, for example, knives and files. Care 30 must be taken in performing this step of the process to remove only such material from the lower portion of the cast as will produce a cast corresponding in shape to a regular last while being especially adapted at its upper portion to 35 meet the requirements of the particular foot for which it is to be used. Figs. 4 and 5 show a "Hydrocal" cast 26 at this stage of the process and it will be noted in Fig. 4 that the upper portion 27 of the cast has been made to correspond in shape to the cone of a regular last.

After the shaping or forming operation has been completed, the sole pattern, which until now has adhered to the bottom of the cast, may be torn off since it has served its purpose and 45 is of no further use in the process. The other cast 10 of the pair should, of course, be prepared in a similar manner so that there will now be completed a pair of last-shaped "Hydrocal" casts 26 corresponding in size and shape to the feet 50 of the individual for whom they were made.

The "Hydrocal" casts 26 are now ready for the final steps of the process disclosed herein and, accordingly, each cast is covered with textile fabric material 28, such as a sock or stocking, which is drawn tightly over the surface of the cast and firmly secured at the top by suitable means such, for example, as a cord or a piece of wire. The fabric material utilized in this step of the process should be woven or knit- 55 ted and of such texture that it will yield and stretch sufficiently to hug the cast tightly and smoothly without wrinkling, folding or becoming otherwise irregular in shape as it is pulled over the cast. It will be understood, however, that 60 the present invention is not limited in its scope to the use of a sock or stocking for covering the cast but is intended to include any fabric material which is sufficiently yieldable to give the desired results. The terms "sock" and "stocking", 65 therefore, are used herein in a comprehensive sense to include any fabric material of this general nature. When fabric materials which do not conform naturally to the shape of a foot in the manner of a stocking are used, however, it 70 will be necessary to cut them to approximately 75

the shape of the cast which is to be covered and to secure them together in some way, for example by stitching, to form one complete covering before they are drawn over the cast. Also, such materials should be cut a little under size so that they will stretch when they are drawn over the cast to hug it tightly at all points. 5

After the fabric material has been drawn over the cast and secured at the top in the manner described, the cast is treated with a stiffening solution 30 (Fig. 7), containing cellulose or a derivative thereof dissolved in a suitable solvent, this solution preferably being of such nature that it will penetrate into the material and saturate all portions of the fabric covering so that when the 10 solvent contained in the solution has evaporated, the fabric will stick tightly to the cast and will harden thereon to form a solid wall or shell on the outer surface of the cast. This stiffening solution 15 may be applied to the fabric material by means of a brush or in any convenient manner that will spread the solution evenly over all portions of the 20 cast.

Substances which can be used for this purpose are numerous since many coating solutions containing cellulose derivatives such as cellulose esters, for example pyroxylin, may be applied to fabric materials in the manner described, and will, upon evaporation of the solvents contained therein, harden sufficiently to produce the desired 25 results. It has been found in practice that pyroxylin dissolved in acetone or other suitable solvent provides an excellent coating solution which can be applied conveniently to the fabric material covering the cast and that this solution will harden 30 sufficiently upon evaporation of the solvent to produce a smooth, solid coating on the surface of the cast. The term "pyroxylin lacquer", however, as used hereinafter in the specification and claims, is intended to include not only pyroxylin dissolved 35 in acetone but any coating substances containing cellulose or a derivative thereof dissolved in suitable solvents. 40

When the coating of stiffening solution which has been applied to the fabric covering of the cast 45 has completely dried out, a second coating of the solution is brushed over the first coating. The second coating of stiffening solution, however, will not penetrate as completely into the fabric material as the first coating did but will remain 50 more on the surface and, consequently, will act to coat the cast with a fairly uniform covering of pyroxylin, thus giving the surface of the cast a smooth and somewhat glossy appearance after the 55 solvent has evaporated. After allowing sufficient time for the second coating of stiffening solution to become thoroughly dry, a second stocking 32 is pulled over the cast, this stocking covering the cast in the same manner as before and being fastened at the top by a cord or wire. The second 60 stocking will also have a tendency to stretch and hug the surface of the cast, thus insuring a smooth, snug fit at all curved or hollow portions of the cast. A coating of pyroxyline lacquer 34 is now 65 brushed over this stocking and, after this coating has penetrated into the fabric and has thoroughly dried so that the cast presents a hard and comparatively smooth surface, a second coating is applied to cover the cast in precisely the same manner as was described in connection with the 70 treatment of the first stocking. The second coating of pyroxylin is allowed to become thoroughly dry, care being taken not to handle the cast and thus prevent it from taking on a smooth, glossy 75 finish when the pyroxylin solution is completely 80

dry. The finished cast 36 (see Fig. 6) is now in condition to be used, having a solid "Hydrocal" core and being reinforced on its surface with a plurality of coatings of fabric impregnated with hardened pyroxylin.

It has already been pointed out that if the measurements of the bottom surface of the cast indicate that the feet are defective or unbalanced with respect to the main arches, a somewhat different mode of procedure is necessary to produce casts suitable for such feet. The method in this case differs only in the step which involves the positioning of the cast on the last bed prior to the addition of the plastic material required for forming the cast to the shape of a last. Accordingly, the manner of positioning a cast of a defective foot on the last bed will now be described.

As stated, if the measurements indicate that the feet of the individual are unbalanced with respect to the main arches, extra plastic material or a "form" must be added to the bottom surface of each cast in order to provide extra space in the finished shoe for the insertion of a filler piece especially adapted to support these arches and to lift them into normally balanced positions. The forms are made to correspond in dimensions to the material of the filler pieces.

Figs. 8, 9, 10 and 11 of the drawings illustrate the manner of positioning and balancing a cast 38 of a deformed foot above the upper surface of a last bed 40. A pin 42, positioned on a sole pattern 44, supports one of the casts 38 at the central portion of the heel end of the cast while the opposite sides of the forepart of the cast are supported by pins 46 and 48. The lengths of the pins upon which the cast 38 is supported are determined by the thickness of the filler piece or inner-mold desired in the finished shoe. It has been found in practice that the best thickness for the filler piece is approximately one-eighth of an inch under those portions of the foot which are substantially normal provided, of course, that no leg shortage exists which would require a thicker filler-piece to support the foot of the shorter leg. A thickness of one-eighth of an inch will provide sufficient support for normal parts of the foot while allowing the filler piece to be made thicker under abnormal portions in order to provide proper support without causing undue bulkiness or clumsiness in the shape of the finished shoe. Consequently, the pin or pins supporting the cast under those portions corresponding to the unbalanced portions of the foot should be cut to such lengths relatively to the one-eighth inch pins that, when the three pins are properly located under the bottom surface of the cast at points corresponding to the three weight-bearing points of the bottom surface of the foot, the cast will be balanced with the back of its heel end in a normal upright position with the vertical center line 50 on the back of the heel end of the cast at right angles to the base of the last bed 40, as shown in Fig. 9. Thus the cast of a defective foot is balanced in a position which corresponds to the position in which the impressions of the feet were made and also to the position in which it is desired that the foot will be supported in the finished shoe.

After the cast has been properly balanced in the manner described, the remaining steps of the process disclosed herein, namely, building a fence 54 around the cast, adding sufficient plastic material 56 to permit the cast to be shaped to the form of a last, as illustrated by the cast 58 in Fig. 11, and reinforcing the cast 58 with suc-

sive coatings of fabric material saturated with a stiffening solution consisting of cellulose or a derivative thereof, are performed precisely in the manner described in connection with the process of making the cast 36 of a normal foot.

The completed filled pyroxylin casts 36 and 60 are shown in Figs. 6 and 12 of the drawings. Since the casts have hardened outer surfaces which are strong enough to withstand the usual pressure and strain incident to the manufacture of shoes, they may, if desired, be used as lasts in the manufacture of ordinary shoes or, if they have been made by the process herein disclosed which provides extra space in the shoe bottom for the insertion of a filler piece, they may be used as lasts in the manufacture of orthopedic shoes for the feet of the individual for whom the casts were made.

As stated, the method herein disclosed also contemplates using the casts as models from which to turn wood lasts with the aid of the usual last-making machine. Lasts obtained by the use of such models will include the peculiar characteristics of the feet of the individual for whom the casts were made so that shoes produced on such lasts will fit the feet properly. The special shapes of the lasts obtained by practicing the present method assures producing a pair of shoes which will not only be comfortable when the individual is sitting down and the weight of the body is taken off the feet, but which will be equally comfortable when the individual is standing and the weight of the body is bearing directly on both feet, or when he is walking and the weight of the body is bearing first on one foot and then on the other. If the feet of the individual are defective with respect to the arches or the cords and ligaments which support the arches, properly fitting orthopedic shoes may be made which will provide extra space for the insertion of filler pieces to support the feet in order to assist in correcting whatever defects of this nature may exist.

While the method as disclosed herein contemplates applying two layers of fabric material impregnated with a liquid stiffening solution to the cast, it is to be understood that two layers of cloth and stiffening solution are used merely to reinforce the surface of the cast to a greater degree than one layer would reinforce it. Accordingly, if one layer of reinforcing materials is found to provide a sufficiently solid covering on the surface of the cast, additional layers of reinforcing materials may be dispensed with. Conversely, if two layers are found to be insufficient, additional layers of reinforcing materials may be applied to the surface of the cast.

Having thus described my invention, what I claim as new and desire to secure by Letters Patent of the United States is:

1. That improvement in methods of making lasts which consists in making a cast of a foot, adding material to the lower portion only of said cast, and shaping the cast to the form of a last.

2. That improvement in methods of making lasts which consists in making a plaster cast of a foot from an impression taken while the foot is sustaining the weight of the body, adding plastic material to the lower portion of said cast, and shaping the cast to the form of a last.

3. That improvement in methods of making lasts which consists in producing a model by making a cast of a foot from a mold obtained while the foot is supporting the weight of the

body, adding plastic material to a portion of the cast while retaining the shape of the foot at other portions, and shaping the cast to the form of a last.

5 4. That improvement in methods of making lasts which consists in making a cast of a foot from an impression made while the foot is in the position that it is to assume in a finished shoe, adding material to increase the length of 10 the cast, and shaping the cast to the form of a last appropriate for said foot, the shaping being done in accordance with measurements taken from the foot.

15 5. That improvement in methods of making lasts for use in the manufacture of orthopedic shoes in which the foot is supported by means of a filler piece which consists in making a cast of a foot, adding plastic material to the bottom surface of the cast so that a cast may be made 20 which corresponds in dimensions to the dimensions of the original cast plus the filler piece, and shaping the last-mentioned cast to the form of a last.

25 6. That improvement in methods of making lasts for use in the manufacture of orthopedic shoes in which the foot is supported by means of a filler piece which consists in making a cast of a foot which is supporting the weight of the body, adding to the bottom surface of the cast 30 plastic material to produce a cast which corresponds in dimensions to the dimensions of the foot plus the filler piece, and shaping said cast to the shape of a last which will provide space for a filler piece in the bottom of a shoe made 35 thereon.

40 7. That improvement in methods of making lasts for use in the manufacture of orthopedic shoes in which the foot is supported by means of a filler piece which consists in producing a model by making a cast of a foot which is in the position that it is to assume in a finished shoe, adding to the bottom surface of the model a form 45 which corresponds in dimensions to the material of the filler piece, and shaping the model to the form of a last thereby producing a model from which to obtain a wood last.

50 8. That improvement in methods of making lasts which consists in making a cast of a foot, adding material to the lower portion of the cast, shaping the cast to the form of a last, and reinforcing the outer surface of the cast with a stiffening composition.

55 9. That improvement in methods of making lasts which consists in making a cast of a foot which is supporting the weight of the body, adding plastic material to the toe and heel portions of the cast, shaping the cast to the form of a last, and reinforcing the surface of the cast with a stiffening medium.

60 10. That improvement in methods of making lasts which consists in making a cast of a foot which is in the position that it is to assume in a finished shoe, adding material to the lower portion of the cast thereby increasing its length, shaping the cast to the form of a last, and reinforcing the surface of the cast with fabric material saturated with a stiffening solution.

65 11. That improvement in methods of making lasts for use in the manufacture of orthopedic shoes in which the foot is supported by means of a filler piece which consists in obtaining a cast of a foot from an impression made while the foot is supporting the weight of the body, adding to the bottom surface of the cast a form which 70 corresponds in dimensions to the dimensions of

the filler piece, shaping the cast and form to the shape of a last, and reinforcing the surface of the cast with a stiffening composition.

12. That improvement in methods of making lasts for use in the manufacture of orthopedic shoes in which the foot is supported by means of a filler piece which consists in making a cast of a foot which is supporting the weight of the body and is in the position that it is to assume in a finished shoe, adding to the bottom surface of the cast a form which corresponds in dimensions to the material of the filler piece, shaping the cast and form to the shape of a last, and reinforcing the surface of the cast with fabric material saturated with a stiffening solution. 15

13. That improvement in methods of making lasts which consists in making a cast of a foot, adding plastic material to the cast, and shaping said cast to the form of a last, thereby producing 20 a model for a wood last.

14. That improvement in methods of making lasts which consists in obtaining an impression of a foot while the foot is supporting the weight of the body, making a cast of the foot from said impression, and producing a model for a wood last by adding material to the lower portion of the cast and then shaping said cast to the form of a last. 25

15. That improvement in methods of making lasts which consists in obtaining an impression of a foot while the foot is in the position it is to assume in a finished shoe, making a cast of the foot from said impression, adding material to fill in the depressions at the toe and heel portions of the cast, and shaping the cast to the form of a last so that it may thereafter be used as a model for turning a wood last on a last lathe. 30 35

16. That improvement in methods of making lasts for use in the manufacture of orthopedic shoes in which the foot is supported by means of a filler piece which consists in making a cast of a foot, adding to the bottom surface of the cast a form which corresponds in dimensions to the material of the filler piece, shaping the cast and form to the shape of a last, thereby producing a model for a wood last. 40 45

17. That improvement in methods of making lasts for use in the manufacture of orthopedic shoes in which the foot is supported by means of a filler piece which consists in obtaining an impression of a foot while the foot is supporting the weight of the body, making a cast of the foot from said impression, adding plastic material to the bottom surface of the cast to produce a form which corresponds in dimensions to the material of the filler piece, and shaping the cast and added material to the shape of the last. 50 55

18. That improvement in methods of making lasts for use in the manufacture of orthopedic shoes in which the foot is supported by means of a filler piece which consists in obtaining an impression of a foot while the foot is in the position it is to assume in a finished shoe, making a cast of the foot from said impression, adding to the bottom surface of the foot a form which corresponds in dimensions to the material of the filler piece, shaping the cast and form to the shape of the last, and adding stiffening materials to the surface of the cast to produce a model for a wood last. 60 65

19. That improvement in methods of making lasts which consists in making a cast of a foot, adding material to the lower portion only of said 70 75

cast, shaping the cast to the form of a last, and reinforcing the surface of the cast with a stiffening composition to produce a model for a wood last.

5 20. That improvement in methods of making lasts which consists in making a cast of a foot which is supporting the weight of the body, adding plastic material to the lower portion of the cast, shaping the cast to the form of a last, and 10 reinforcing the surface of the cast with a plurality of coats of stiffening materials thereby forming a model for the reproduction of a wood last.

15 21. That improvement in methods of making lasts which consists in making a cast of a foot which is supporting the weight of the body and is in the position that it is to assume in a finished shoe, adding a strip of material to the lower portion of the cast, shaping the cast to the form of a last, and reinforcing the surface of the cast with fabric materials saturated with a stiffening solution to produce a model for a wood last from the reinforced cast.

25 22. That improvement in methods of making lasts for use in the manufacture of orthopedic shoes in which the foot is supported by means of a filler piece which consists in making a cast of a foot, adding to the bottom surface of the cast a form which corresponds in dimensions to the 30 material of the filler piece, shaping the cast and form to the shape of a last, and reinforcing the last-shaped cast with a pyroxylin stiffening composition so that said cast may be utilized as a model for making a wood last.

35 23. That improvement in methods of making lasts for use in the manufacture of orthopedic shoes in which the foot is supported by means of a filler piece which consists in making a cast of a foot which is supporting the weight of the body, adding to the bottom surface of the cast a form which corresponds in dimensions to the material of the filler piece, shaping the cast and form to the shape of a last, and reinforcing the surface of the cast with a plurality of coats of pyroxylin covered stiffening materials so that 40 the cast may be utilized as a model from which to turn a wood last with the aid of the usual last-making machinery.

45 24. That improvement in methods of making lasts for use in the manufacture of orthopedic shoes in which the foot is supported by means of a filler piece which consists in making a cast of a foot which is supporting the weight of the body and is in the position that it is to assume in a finished shoe, adding to the bottom surface of the cast a form which corresponds in dimensions to the material of the filler piece, shaping the cast and form to the shape of a last, reinforcing the surface of the cast with fabric materials saturated with a solution of cellulose or a derivative thereof thereby stiffening said cast so that it may be utilized as a model.

50 25. That improvement in methods of making lasts which consists in making a cast of a foot, adding plastic material to the toe and heel portions of the cast, shaping the cast to the form of a last, and reinforcing the cast with fabric material stiffened with a solidifying solution of cellulose materials.

55 26. That improvement in methods of making lasts which consists in making a cast of a foot from an impression taken while the foot is supporting the weight of the body, adding plastic material to the toe and heel portions of the cast, shaping the cast to the form of a last, and rein-

forcing the cast with layers of fabric saturated with a solution of pyroxylin.

27. That improvement in methods of making lasts which consists in making a cast of a foot from an impression taken while the foot is supporting the weight of the body, adding plastic material to the toe and heel portions of the cast, shaping the cast to the form of a last, covering the cast with a sock, and coating the sock with a cellulose derivative dissolved in a solvent.

10 28. That improvement in methods of making lasts which consists in making a cast of a foot from an impression taken while the foot is in the position it is to assume in a finished shoe, adding material to the toe and heel portions of the 15 cast, shaping the cast to the form of a last, fitting a stocking on said cast, stiffening the stocking with a plurality of coats of pyroxylin lacquer, fitting a second stocking on the cast, and stiffening the second stocking with a plurality of 20 coats of pyroxylin lacquer to form a hard coating on the surface of the cast.

29. That improvement in methods of making lasts for use in the manufacture of orthopedic shoes in which the foot is supported by means of a filler piece which consists in making a cast of a foot from an impression taken while the 25 foot is supporting the weight of the body, adding to the bottom surface of the cast a form which corresponds in dimensions to the material of the 30 filler piece, shaping the cast and form to the shape of a last, and reinforcing the cast with knitted fabric material stiffened with a solidifying solution of cellulosic material to form a model from which a wood last may be produced.

35 30. That improvement in methods of making lasts for use in the manufacture of orthopedic shoes in which the foot is supported by means of a filler piece which consists in obtaining an impression of a foot in a foot mold while the foot 40 is supporting the weight of the body and is in the position that it is to assume in a finished shoe, making a cast of the foot from said impression, adding to the bottom surface of the cast a form which corresponds in dimensions to the material 45 of the filler piece, shaping the cast and form to the shape of a last, and reinforcing the cast with layers of knitted fabric material saturated with a solution of cellulose or a derivative thereof.

50 31. That improvement in methods of making lasts for use in the manufacture of orthopedic shoes in which the foot is supported by means of a filler piece which consists in making a cast of a foot from an impression taken while the foot is supporting the weight of the body and is in 55 the position that it is to assume in a finished shoe, adding to the bottom surface of the cast a form which corresponds in dimensions to the material of the filler piece, shaping the cast and form to the shape of a last, fitting a sock over 60 said cast, impregnating the sock with a plurality of stiffening coatings of pyroxylin lacquer, fitting a second sock over the cast, impregnating said second sock with a plurality of coatings of pyroxylin lacquer thereby producing a model 65 from which a wood last may be obtained with the aid of the usual last-making machinery.

32. That improvement in methods of making lasts for use in the manufacture of orthopedic shoes in which the foot is supported by means of a filler piece which consists in making a cast of a foot from an impression taken while the 70 foot is in the position it is to assume in a finished shoe, supporting said cast in a predetermined position above the upper surface of a 75

- last bed, said upper surface being shaped to conform to the bottom surface of a regular last having a toe spring and heel height appropriate for said cast, adding to the bottom surface of the cast a form which corresponds in dimensions to the material of the filler piece, shaping the cast and form to the shape of a last, reinforcing the surface of the cast with a plurality of layers of knitted fabric material, and impregnating each layer with pyroxylin dissolved in acetone to harden said fabric material. 33. That improvement in methods of making lasts for use in the manufacture of orthopedic shoes in which the foot is supported by means of a filler piece which consists in making a cast of a foot from an impression taken while the foot is supporting the weight of the body and is in the position that it is to assume in a finished shoe, producing a pattern appropriate in size for said cast, locating said pattern on the upper surface of a last bed, said upper surface being shaped to conform to the bottom surface of a regular last having a toe spring and heel height suitable for said cast, supporting the cast in a predetermined position above said pattern, said position corresponding substantially to the position in which the foot is to be supported in the finished shoe, adding to the bottom surface of the cast a form which corresponds in dimensions to the material of the filler piece, shaping the cast and form to the shape of a last, covering the cast with a plurality of layers of knitted fabric material, and reinforcing the fabric material with successive coatings of a solution of pyroxylin or other cellulose derivative. 34. That improvement in methods of making lasts which consists in making a cast of a foot and adding sufficient material to the lower portion of the cast to give said portion the shape of a last while retaining the shape of the foot at the upper portion of the cast. 35. That improvement in methods of making lasts which consists in making a cast of a foot which is in weight-bearing position, adding plastic material to the lower portion of the cast while retaining the shape of the foot at the upper portion, and shaping said lower portion to the form of a last. 36. That improvement in methods of making lasts which consists in producing a cast of a foot which is sustaining the weight of the body, adding plastic material to the cast, said material covering substantially less than the entire surface of the cast, and shaping the covered portion of the cast to the form of a last while retaining the shape of the foot at other portions of the cast. 37. That improvement in methods of making lasts which consists in making a cast of a foot, adding plastic material to the toe portion of the cast, and shaping the cast to the form of a last.
